UNITED STATES PATENT OFFICE.

PATRICK HENRY CUMMINS, OF AMSTERDAM, NEW YORK.

SIDE FRAMING FOR SLEIGHS.

1,040,897.

Specification of Letters Patent.

Patented Oct. 8, 1912.

Application filed November 17, 1911. Serial No. 660,865.

To all whom it may concern:

Be it known that I, PATRICK H. CUMMINS, a citizen of the United States, residing at Amsterdam, in the county of Montgomery 5 and State of New York, have invented certain new and useful Improvements in Side Framing for Sleighs; and I do hereby declare the following to be a full, clear, and exact description of the invention, such as 10 will enable others skilled in the art to which it appertains to make and use the same.

This invention relates to side framing for sleighs and has for an object to provide a side framing constructed of T-iron or its 15 equivalent and with means for supporting a bolster.

A further object of the invention is to provide a side framing for a sleigh constructed of T-iron having the web offset 20 from the line of the center, either by forming the flanges of unequal width or by inclining the web from a perpendicular.

A further object of the invention is to provide improved supporting means for the 25 center or upstanding portion of the knee member.

A further object of the invention is to provide improved means for attaching a shoe to a sleigh runner.

With these and other objects in view the 30 invention comprises certain novel constructions, combinations and arrangement of parts as will be hereinafter more fully described and claimed.

In the drawings: Figure 1 is a perspective view of the side framing which forms the 35 subject matter of this application. Fig. 2 is a view in side elevation of the side framing seen from the side opposite that shown in Fig. 1 and showing a conventional bolster 40 attached thereto. Fig. 3 is a top plan view of the side framing showing the position of a conventional bolster in dotted lines. Fig. 4 is a detail sectional view taken on line 4-4 of Fig. 2. Fig. 5 is a detail view 45 of the top bend of the knee. Fig. 6 is a transverse sectional view taken on line x-x of Fig. 2, showing the preferred construction with the web of the T-iron offset from 50 the center forming flanges of unequal widths. Fig. 7 is a transverse sectional view taken on line x-x of Fig. 2 showing the web offset by being bent from a perpendicular. Fig. 8 is a top plan view of a fragment 55 of a T-iron runner with the web offset

locally to permit the passage of a shoe securing bolt centrally through such runner. Fig. 9 is a transverse sectional view through a T-iron runner showing the web offset to 60 permit the passage of a bolt through the runner and through an attached shoe to be secured by bending over the top of the web. Fig. 10 is an inverted plan view of one end of the bolster showing the gains provided to 65 receive the connecting means.

Like characters of reference indicate corresponding parts throughout the several views.

The improved side framing which forms the subject matter of this application comprises a runner shown as a whole at 10 constructed of T-iron, such runner being curved at the forward end, as at 11, preferably on the arc of a circle, with the web 12 of the T-iron on the upper side of the runner 70 proper and the inner side of the curve.

A knee, shown as a whole at 13, is formed by producing reverse segments, as indicated at Figs. 1 and 2, having its upper end formed as indicated especially at Fig. 5 and with lower oppositely extending extremities secured to the runner 10 at spaced points, as by the rivets 14. The knee is also constructed of T-iron and the webs of the knee and of the runner are offset from the 75 line of the center of the flange, as indicated at Fig. 6, or in inclined position as shown at Fig. 7, so that the flanges of both the knee and the runner will register vertically, as indicated in both said Figs. 6 and 7.

To support and strengthen the upwardly extending part of the knee a tube or pipe 15 is employed being bifurcated at its lower end as indicated at Fig. 4 and positioned to 80 embrace the web 12 and secured thereto as by the rivet 16. At its upper end the pipe 15 receives a stud 17 which is inserted into the end of such pipe, being formed as a reverse bend of a rod which, constructed as a Y at 18, is seated in a notch 19 in the web 85 of the knee, such notch being shown in Fig. 5, and embracing the flanges as shown in Fig. 4. The rod is then bent to form a horizontal section 20 for supporting a bolster 90 shown conventionally at 21, and to strengthen and hold the knee and runner in their relative positions, and is further formed in a downwardly extending U 22 to embrace the rear end of the knee in the web of which a notch 95 is formed and into said notch the U is 100 105 110

- seated, as shown in Fig. 1 for supporting the rave shown as a whole at 23, to which it is clamped by a plate 24, shown in section in Fig. 4. The rear end of the rave 23 is further supported by means of braces 25 which are also clamped between the plate 24 and the web of the rave and extend in an inclined position downwardly and are secured to the knee as by the rivets 26.
- 10 The rave 23 is likewise constructed of T-iron with the web offset from the line of the center so that where it connects at the forward end with the runner 10 it can be secured by a rivet 27 with the flanges of the 15 top of the rave and the bottom of the runner registering. The rave is further strengthened in its position by a brace bar 28 secured as by rivets 29 to the rave and extending backwardly is given a twist as at 20 30 to form a substantially horizontal plane portion 31 which is seated beneath the bolster 21.

As it is desirable to have the bolster oscillate relative to the side framing, there has 25 been shown in Figs. 2 and 10 a means for allowing such oscillation consisting of gains 32 cut out from the bolster forming an apex 33 which will permit the bolster to rock and the same is held in position by means of 30 threaded extremities 34 formed upon the rod 20 and a longitudinally extending gain accommodates the lateral section of such rod. The angle between the forward end of the rave 23 and the forward end of the runner 35 10 is preferably strengthened by a brace 35 which is provided with an eye 36 to apply draft to the side frame.

It is desirable to attach a shoe to a runner constructed in accordance with the foregoing description and for that purpose holes are formed through the runner as indicated at 37 in Fig. 1 where the web 12 is offset from the center. In employing the ordinary T-iron with the web at the center it is necessary to especially offset a portion of the web, as shown at 38 in Figs. 8 and 9 to receive the holes 37 to permit a bolt to pass therethrough. To secure a shoe in position upon the under side of the runner, which 50 said shoe is shown at 39, the bolt at 40 is bent over to form a hook engaging the top of web 12.

I claim:

1. In the side framing of a sleigh, a runner constructed of T-iron with the web offset from the line of the center and a superstructure built upon and connected with the runner and having a web offset reversely from the line of the center with the flanges of the connected parts registering.
2. In the side framing of a sleigh, a runner constructed of T-iron having its web offset from the line of the center and a knee constructed of T-iron having reversely extending extremities with webs offset from

the line of the center connected with the offset web of the runner and with the flanges of the knee and runner registering.

3. In the side framing of a sleigh, a runner constructed of T-iron having its web offset from the line of the center, a knee constructed of T-iron with the web offset from the line of the center and with the webs of the knee and runner reversed and connected, and a rave constructed of T-iron having its web offset from the line of the center and connected with the offset web of the runner.

4. In the side framing of a sleigh, a runner constructed of T-iron with the web offset from the line of the center and a knee constructed of T-iron with its web offset from the line of the center and formed as the reverse arcs of a circle with the oppositely extending extremities secured by their offset webs to the offset webs of the runner at 85 spaced points.

5. In the side framing of a sleigh, a runner constructed of T-iron, a knee constructed of T-iron and as an upwardly extending loop, a pipe bifurcated at its lower end embracing the web of the runner, a rod constructed as a Y at one end to receive the knee and a stud extended into the upper end of the pipe.

6. In the side framing of a sleigh, a T-iron runner having a portion of the web deflected from the center line and with holes formed through such runner to receive a shoe securing bolt.

7. In the side framing of a sleigh, a runner composed of T-iron having its web offset from the center and with a hole through the runner, a shoe disposed beneath the runner, and a bolt inserted through the shoe and hole and provided with means bearing 105 upon the top of the runner to maintain such bolt in position.

8. In the side framing of a sleigh, an upwardly extending knee, a rave spaced laterally from the knee, and a bolster having gains cut in its lower surface inclined in opposite directions from the center and disposed upon the knee and rave and a gain connecting the middle points and the two first mentioned gains.

9. In the side framing of a sleigh, an upwardly extending knee, a rave spaced laterally from the knee, fastening means extending upwardly upon the exterior sides of the knee and rave, and a bolster having openings to secure the fastening means and gains formed in the under side inclined in opposite directions from the center and receiving the knee and rave, and a gain connecting the two first mentioned gains.

10. In the side framing of a sleigh, a T-iron runner, a T-iron knee secured to the runner and having a notch in the web of the uppermost portion of the knee, a strut bifurcated at its lower end engaging the web of 130

the runner, and a Y-shaped rod inserted in the top of the strut and embracing the web of the knee at the notch.

11. In the side framing of a sleigh, a T-
5 iron runner, a T-iron knee, a hollow strut
engaging at its lower end the runner, a Y-
shaped rod inserted in the top of the strut
and embracing the web of the knee and posi-
10 tioned in a notch formed in the under side
of the web of such knee, and a bolster se-
cured to the Y-shaped rod.

12. In the side framing of a sleigh, a T-
iron runner, a T-iron knee, a T-iron rave,
provided with a notch, offset laterally from
15 the center of the knee, a Y-shaped rod hav-
ing its lower end supported above the run-
ner and one extremity engaging the notch of
the rave.

13. In the side framing of a sleigh, a T-
20 iron runner having its web offset from the

center, a T-iron knee having its web offset
from the center with the webs connected in
reverse order so that the flanges of the knee
and the runner register, a brace inserted be-
tween the runner and the upwardly extend-
25 ing part of the knee, a brace offset inwardly
from the top of said first mentioned brace,
and a T-iron rave having its web offset from
the center and connected with the offset web
at the front end of the runner in reverse po-
30 sition so that the flanges register, said rave
being also bent and supported by the ex-
tremity of the last mentioned brace.

In testimony whereof I affix my signature
in presence of two witnesses.

PATRICK HENRY CUMMINS.
